UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF NEW HAMPSHIRE.

SUCTION APPARATUS.

Application filed December 12, 1921. Serial No. 521,895.

To all whom it may concern:-

Be it known that I, HOWARD PARKER, a citizen of the United States, and a resident of Berlin, county of Coos, State of New

5 Hampshire, have invented certain new and useful Improvements in a Suction Apparatus, of which the following is a specification.

It is the common practice in the art of paper making to suspend particles of paper 10 pulp in a liquid and collect them on an apron or felt in the form of a wet sheet or web which is passed between rolls of one sort or another, depending on the manner or purpose of manipulating the pulp. In 15 passing the wet felt and the web of pulp thereon between the rolls, some of the water carried thereby is squeezed out and unless properly taken care of will accumulate and set up a back pressure in the angle at the

20 entrance side of the rolls resulting in dis-coloration, non-uniformity, wrinkling, break-age or other faults in the pulp web. The accumulation of water at the entrance angle between the squeeze rolls is particularly ob-

25 jectionable where one of the rolls is in the form of a mandrel onto which the web of pulp is wound in a series of convolutions in order to build up a tube. In thus winding the web of pulp to form a tube, it is desir- 30 able, in order to facilitate the felting of the fibres in the successive convolutions and thus produce a more or less homogeneous tube free from liability to split or show laminations, to wind the web of pulp onto the

35 mandrel in as wet a condition and under as great a pressure as are practical. However, the greater the pressure with which the pulp is squeezed between the mandrel and its co-operating roll, the greater is the tendency 40 for the water to accumulate at the entrance angle between the rolls, and this accumula- 45 tion of water not only causes faults in the web as it is brought up to the winding point, but also tends to soften the pulp already wound onto the mandrel and results in a distorted and seamed or wrinkled tube wall.

The aim of the present invention is to 50 provide an arrangement for effectively tak- 55 ing care of the water which tends to accumu- late at the entrance angle between the rolls 60 between which the web of pulp is passed and pressed. By means of the present in- 65 vention, the web of pulp as it is laid onto the mandrel may contain a greater percent- 70 age of water than has heretofore been prac-

tical and the web may be pressed harder than at present without danger of the sur- 75 plus water which is squeezed out causing faults in the web or injuring the tube.

The device of the present invention will 80 here be described with reference to its use in connection with a tube winding machine and to which use it has peculiar adaptability, but it is to be understood that the present disclosure is by way of illustration only and 85 is not to be taken as restrictive of my con- 90 ception. Furthermore, while I have shown but one embodiment of my invention in the accompanying drawings, this showing is by way of exemplification only, the invention 95 being susceptible of various modifications and changes in construction and arrange- 100 ment which would be within the spirit of the invention.

In the accompanying drawings:

Fig. 1 is a diagrammatic lay-out showing 105 a web forming machine and so much of a tube winding machine as is necessary to illustrate the application of the present in- 110 vention.

Fig. 2 is a diagrammatic view showing 115 the suction box in plan, and the web of pulp developed in a plane between the suction box and the line of squeeze between the rolls.

Fig. 3 is an elevational view of the suction 120 box looking at that surface thereof which lies against the base roll.

Fig. 4 is a sectional view taken on line 125 4-4 of Fig. 3, and

Fig. 5 is a sectional view taken on line 130 5-5 of Fig. 3.

In Fig. 1 of the accompanying drawings 135 the felt *a* takes the pulp from the cylinder mold *b* of the web forming machine and carries it to the mandrel *c* positioned be- 140 tween the base rolls *d*, *d'*, and a press roll *e* of the tube winding machine. The web forming machine may, of course, be of any suitable construction, that shown in the drawings being by way of illustration only. 145 The pulp may be on a wire when the pulp is intended to form a sheet. Only a portion of the tube winding machine is illus- 150 trated as the particular type thereof is im- 155 material so far as the present invention is concerned. As the wet web of pulp passes between the base roll *d* and the mandrel *c*, it leaves the felt and is wound convolutely 160 upon the mandrel into the form of a tube. 165

For convenience in description it may be stated here that, in one manner of speaking, the mandrel *c* and the base roll *d* constitute a pair of squeeze rolls between which the 5 felt with the web of pulp thereon is passed and pressed. The "entrance angle" between the squeeze rolls is denoted by the arrow *g* and the "line of squeeze" (that is the line along which the web of pulp and felt are 10 pressed between the squeeze rolls), is indicated by the letter *h*. It will be noted that the felt *a* is lapped onto the base roll *d*, as at *h*, in advance of the "line of squeeze."

In accordance with the present invention 15 the suction box *M*, which of itself embodies features of novelty and advantage, is positioned at the lap of the felt on to the base roll *d*, and this suction box, the base roll *d* and the felt with the web of pulp thereon 20 are so arranged and coordinated that the force of suction set up is effective in carrying away the water pressed out at the line of squeeze, thus practically preventing accumulation of water in the entrance angle *g*. 25 The suction box is greater in length than the width of the felt and has a chamber *11* from which air and water are drawn through the outlets *12* at the ends of the box. The front or forward face of the suction 30 box is curved concentrically to and fits against the periphery of the base roll *d*. The top surface *14* of the suction box is substantially at a tangent to the base roll *d* and meets the forward face of the suction box in 35 a narrow lip or nozzle *15* which is less in length than the width of the felt *a* and the web of pulp thereon. Leading from the forward face of the suction box to the chamber *11* is a narrow throat or slot *16*. Extending 40 transversely across the forward face of the suction box and positioned beneath the throat *16* is a packing *17* closely engaging the base roll *d* and forming a substantially fluid tight joint therewith. Leading 45 from the lip *15* to the slot *16* are diagonally disposed or inclined channels *19*. The surface *20*, in which these channels are disposed, closely fits the circumference of the base roll *d*. Positioned adjacent each side 50 edge of the forward face of the suction box and extending from the packing *17* to beyond the lip *15* is a packing *22* which fits against the base roll. It will be noted that the upper end of each of the packings *22* 55 tapers down to a point and provides a sealing member completely filling the angle between the side edge of the felt and the base roll clear up to the line of lap. As previously stated, the lip *15* of the suction 60 box is lesser in length than the widths of the felt *a* and the wet web of pulp thereon. The side edges of the felt *a* and the pulp web thereon overlap and ride on the sealing members *23*. The packings *22* and *17* form 65 fluid tight seals along each side edge of the

face *13* and below the throat *16*, and as the projecting ends or sealing members *23* of the packings *22* effectively seal the ends of the space between the lip *15* and the lap of the felt on the base roll *d* it follows that air 70 or water can only be drawn into the suction box from or through the felt and the web of pulp.

A possible explanation of the operation of the arrangement described may now be 75 given with particular reference to Fig. 2, the showing of this figure being diagrammatic and in some respects exaggerated for convenience in illustration.

The felt *a* picks up the pulp from the cylinder-mold *b* in a heavily saturated condition and carries it, more or less in this condition over the lip *15* and the air seal members *23* of the suction box. In this condition the pulp fibres are loosely felted on the felt, that is to say they are more or less held apart in a state of semi-suspension in the water, so that the web is somewhat porous or pervious. On reaching the lip *15* of the suction box, the action of the vacuum within this box is immediately brought to bear to draw out, at least, some of the excess water from that portion of the felt and web located between the sealing members *23*. As a result the felt fibres of that portion of the pulp web which passes directly over the lip are more closely held together thus creating a slightly tighter mat of pulp which is, relatively speaking, more air tight than it was previous to the extraction of this excess water (although it still possesses a high percentage of water).

The border portions of the felt and web which pass over the sealing members *23* are not directly acted upon by the vacuum exerted at the lip of the suction box. Thus the web of pulp on the felt is divided into three bands or areas—one in the center consisting of a slightly consolidated mat of pulp fibres, from which at least some of the excess water has been extracted to form a slightly more impervious wall to the passage of air through its texture; and a border zone at each side of the web carrying in their travel from the suction box to the line of squeeze an excess of water enmeshed in the pulp deposit. The excess water which remains in the border portions or zones of the felt and web of pulp results in practically fluid tight seals between these borders and the base roll *d* which bar the ingress of air under the edges of the felt.

The effect of the vacuum set up in the suction device on the water carried by the felt and the web of pulp is graphically shown in Fig. 2. It will be evident that the force of suction which is present under the felt and web will tend to draw out excess water from the border zones so that these zones gradually decrease in width towards

the line of squeeze. It may be assumed that if there were no back pressure resulting at the line of squeeze, the border zones would be partially exhausted of excess water along 5 the line x, x' . The felt and web are moved at such a rate of speed that a particle of excess water x^3 at the very edge of the web of pulp will not be exhausted from the border zone before this particle of water reaches 10 the line of squeeze and thus the air seal along each side of the web is maintained from the line of the lip of the suction box clear up to the line of squeeze. In actual practice it is found that the water which is 15 pressed out at the line of squeeze and flows underneath the central portion of the web to the suction box, is forced outwardly towards the edges of the felt and this action counteracts the tendency of the force of suction 20 to entirely exhaust the border portion of excess water. The dotted lines y represent the direction of the hydraulic force exerted by the squeeze to the rolls.

As the pulp deposit on the felt in moving 25 forward arrives at the line of squeeze between the mandrel and the base roll d , the heavy pressure exerted therebetween forces an additional amount of water out of the pulp web and this water tends to back up or 30 accumulate in the entrance angle g . In analyzing the action which takes place it may be assumed that the water which is pressed out comprises three portions, the first portion being that which is forced under the 35 felt and over the surface of the roll d ; the second portion being that which is forced back into the felt and web intermediate the line of squeeze; and the third portion, that which tends to collect in the entrance angle 40 g . The first portion is forced back under the felt which has been partially exhausted of the excess water. The second portion tends to enter and distend the pulp web by floating or forcing the fibres apart thus 45 creating a porous zone immediately adjacent the line of squeeze. The result is that a water channel is provided between the underside of the felt and the base roll intermediate the edges of the felt and the hydraulic 50 force set up at the line of squeeze tends to force the water back through this channel, and the suction effective at the lip of the suction box draws the water through this channel.

Now, since at least some of the excess water has been withdrawn from the web of pulp between the lip or nozzle of the suction box and the line of squeeze making the pulp between its side edges slightly impervious 55 to water; and since there is an excess amount of water in the web immediately adjacent the line of squeeze, making the web adjacent that line slightly pervious or porous, the resistance offered by the web of pulp to 60 the passage of air and water therethrough is

less immediately adjacent to the line of squeeze than elsewhere. The result is the force of the vacuum will draw the water which tends to accumulate in the entrance angle g down through the web and felt into 70 the channel between the web and the base roll and back into the suction box from which it is carried away. Thus, the accumulation of water in the entrance angle g and the injurious effects thereof on a web 75 and tube are entirely obviated. Furthermore, the tube, when the winding thereof is finished, is drier than would be the case if water were allowed to accumulate in the entrance angle. It is to be understood, of course, that only a part of the excess water is extracted from the felt before it reaches the line of squeeze. When the web of pulp reaches the line of squeeze, it still has a relatively high percentage of water which insures proper union or interfelting of the successive convolutions wound onto the mandrel, which means that a tube wall is produced which is uniform and free from the liability of laminating or splitting. 90

I claim as my invention:—

1. That improvement in the formation of bodies by winding a wet web of pulp onto a mandrel which consists in passing a wet web of pulp on a conveyor between an imperforate 95 base roll and a mandrel, convolutely winding the web of pulp onto the latter, and sucking water from the pulp web at a point between the conveyor and the surface of said roll. 100

2. That improvement in the formation of bodies by winding a wet web of pulp onto a mandrel which consists in passing a wet web of pulp on a porous conveyor between a mandrel and an imperforate base roll, convolutely winding the web of pulp onto the mandrel, and withdrawing water from the web of pulp over the peripheral surface of said roll. 105

3. That improvement in the formation of 110 bodies by winding a wet web of pulp onto a mandrel which consists in passing a wet web of pulp on a conveyor between a mandrel and a base roll after it has been lapped onto the latter, convolutely winding the web of 115 pulp onto the mandrel, and withdrawing water pressed out immediately adjacent the mandrel back under the conveyor and over the surface of the base roll.

4. That improvement in the formation of 120 bodies by winding a web of pulp onto a mandrel which consists in passing a wet web of pulp on a porous conveyor between an imperforate base roll and the mandrel after it has been lapped onto the roll, convolutely winding the web of pulp onto the mandrel, and applying suction at the lap of the conveyor onto the roll for withdrawing water from immediate adjacent the line 125 of squeeze between the mandrel and roll. 130

5. In combination means for winding a web of pulp into a tube and including an imperforate base roll, a mandrel and a pulp web conveyor passing between said mandrel and roll; and means for withdrawing water from immediately adjacent the line of squeeze between said mandrel and roll back over the peripheral surface of said roll.
6. In combination, means for winding a web of pulp into a tube and including an imperforate base roll, a mandrel and a pulp web conveyor passing between said mandrel and roll; and a suction device positioned between said conveyor and the peripheral surface of said roll for withdrawing water from the web.
7. In combination, means for winding a web of pulp into a tube and including an imperforate base roll, a mandrel and a pulp web conveyor passing between said mandrel and roll after it is lapped on the latter, and means for sucking the water pressed out at the line of squeeze back towards the line of lap.
8. In combination, mean for winding a web of pulp into a tube and including an imperforate base roll, a mandrel and a pulp web conveyor passing between said mandrel and roll; and suction means positioned at the lap of the conveyor and said roll for sucking excess water from the web between its side edges.
9. That improvement in the art of paper making which consists in passing a wet web of pulp on a porous conveyor about a roll, applying suction to said web in the space at the lap of the conveyor onto the roll, and employing the conveyor and web for sealing the ends of the space in which the suction is applied.
10. That improvement in the art of paper making which consists in passing a wet web of pulp on a porous conveyor about a roll, applying suction to said web between its edges at a point between said conveyor and the surface of said roll, and employing the wet borders of the web and conveyor for sealing the space in which suction is applied.
11. In combination, a roll, a pulp web conveyor passing thereabout, a suction means positioned at the lap of said conveyor on said roll, and means for preventing excess water from being withdrawn from the borders of said web and conveyor.
12. In combination, a roll, a pulp web conveyor passing thereabout, and a suction device positioned at the lap of said conveyor onto said roll and having sealing members engaging the roll and supporting the borders of the conveyor up to the line of lap.
13. In combination, a roll, a pulp web conveyor passing thereabout, a suction device having a narrow suction nozzle positioned in the angle formed at the lap of the conveyor on said roll, and sealing members at a line spaced from the line of lap, and sucking the ends of said nozzle engaging said roll and supporting the borders of said conveyor substantially up to the line of lap.
14. In combination, a roll, a pulp web conveyor passing thereabout, a suction box positioned between the conveyor and said roll and having a face opposed to the periphery of the latter, and means between the periphery of the roll and said face of the suction box through which water is sucked from the web.
15. In combination, a roll, a pulp web conveyor passing thereabout, a suction box positioned in the angle of the lap of the conveyor onto said roll and having a surface fitting against the peripheral surface of said roll, and a channel in one of said surfaces leading from said angle of lap to the suction space of said box.
16. In combination, a roll; a pulp web conveyor passing thereabout; and a suction box having a face fitting against said roll, a suction chamber, and inclined channels in said face leading from the angle of the lap of the conveyor on said roll to said chamber.
17. A suction device having a body portion provided with a face adapted to engage against the periphery of a roll, a chamber opening into said face, and channels in said face leading from one edge thereof into said chamber.
18. A suction device having a body portion provided with a face adapted to engage against the periphery of a base roll, a lip at one edge of said surface, a chamber opening into said face below said lip, a channel in said face leading from said lip to said chamber, and packings along the sides of said face and below the opening of said chamber into said face and adapted to closely fit against the roll.
19. That improvement in the art of paper making which consists in passing a wet web of pulp on a porous conveyor about a roll, sucking some of the excess water out of the web between its edges at the lap of the conveyor on the roll, and maintaining excess water in the edge borders in the web, and conveyor for preventing air from flowing under the side edges of the conveyor while on the roll.
20. That improvement in the art of paper making which consists in passing a wet web of pulp on a porous conveyor about a roll, squeezing out the excess water from the web along a line spaced from the line of lap of the conveyor on the roll, and sucking the water pressed out at the line of squeeze back between the roll and the conveyor towards the angle of lap.
21. That improvement in the art of paper making which consists in passing a wet web of pulp on a porous conveyor about a roll, squeezing out of the web excess water along a line spaced from the line of lap, and sucking

ing the water pressed out at the line of squeeze back between the roll and the conveyor and intermediate the side borders of the latter.

5 22. That improvement in the art of paper making which consists in passing a wet web of pulp on a conveyor about a roll, squeezing out of the web excess water along a line spaced from the line of lap, maintaining an 10 excess of water in the border portions of the web between the line of lap and the line of squeeze, and sucking the water pressed out at the line of squeeze back under the conveyor between its border portions to the 15 angle of lap.

23. That improvement in the art of paper making which consists in passing a wet web of pulp on a porous conveyor about a roll, squeezing out excess water from the web 20 along a line spaced from the line of lap, sucking water from the web as it is lapped onto the roll, and withdrawing the water pressed out at the line of squeeze back under the conveyor to the angle of lap.

25 24. In combination, a pair of squeeze rolls, a pulp web conveyor passing between said rolls after being lapped on one of them, and suction means spaced rearwardly of the line of squeeze for sucking water pressed out 30 at the line of squeeze back over the surface of said roll.

25. In combination, a pair of squeeze

rolls, a porous web carrying conveyor passing between said rolls after being lapped on one of them, and suction means positioned 35 at the lap of the conveyor onto said roll for sucking excess water from the web and the conveyor between their side edges.

26. In combination, a pair of squeeze rolls, a pulp web carrying conveyor passing 40 between said rolls after it is lapped on one of them, a suction device positioned at the lap of the conveyor onto said roll and having a nozzle of less width than said conveyor, and means for moving the web at 45 such speed that excess water is not exhausted from the borders of the web between the line of lap and the line of squeeze.

27. In combination, a pair of squeeze rolls, a porous web carrying conveyor passing 50 between said rolls after it is lapped on one of them, a suction device positioned at the lap of said conveyor onto said roll and having sealing means engaging said roll and supporting the borders of said conveyor 55 up to the line of lap.

28. In combination, a pair of squeeze rolls, a porous web carrying conveyor passing therebetween after it is lapped on one 60 of said rolls, and suction means for sucking water along the peripheral surface of said rolls out of the angle of lap.

HOWARD PARKER.
